C. J. KUNTZ ET AL

AUTOMOBILE LAMP

Filed Nov. 5, 1923

By *Clarence D. O'Brien*
Attorney

UNITED STATES PATENT OFFICE.

CHARLES J. KUNTZ AND EDWARD A. LAURENT, OF JEANNETTE, PENNSYLVANIA.

AUTOMOBILE LAMP.

Application filed November 5, 1923. Serial No. 672,853.

To all whom it may concern:

Be it known that we, CHARLES J. KUNTZ and EDWARD A. LAURENT, citizens of the United States, residing at Jeannette, in the county of Westmoreland and State of Pennsylvania, have invented certain new and useful Improvements in Automobile Lamps, of which the following is a specification.

This invention relates to electric lamps and has particular reference to headlights for automobiles or other vehicles.

Among objects of the invention is to provide an improved construction of headlights whereby the glare therefrom may be reliably controlled without minimizing the effectiveness of the lights for driving purposes.

A further object of the invention is to provide an improved reflecting structure adapted to concentrate and direct the beam 20 of light upon the roadway downwardly and forwardly in front of the vehicle, while at the same time preventing all glare from the lamp, especially from its lower portion that would tend to be objectionable to parties approaching the vehicle carrying the lamp.

Another object of the invention is to provide means in the nature of an attachment for common or standard forms of lamp casing whereby the several advantages of 30 the invention may be utilized by application to lamps now in use, and without material or extensive change.

Other objects will appear as the nature of the invention is better understood and 35 the same consists in the novel form, combination and arrangement of parts herein-after more fully described, shown in the accompanying drawings and claimed.

In the drawings wherein like reference 40 characters indicate corresponding parts throughout the several views:

Figure 1 is a substantially central vertical longitudinal sectional view of a head-light constructed in accordance with the 45 present invention.

Figure 2 is a front elevational view thereof with the transparent closure plate removed.

Figure 3 is a perspective view of the reflector, and

Figure 4 is a fragmentary front elevational view of the upper adjacent portions of the reflector and casing.

Referring more in detail to the drawing, 55 10 indicates the casing of a conventional headlight, in the open front of which the

usual glass plate or lens 11 is removably secured by means of a rim 12.

The principal element of the improvement comprises a reflector of peculiar form 60 mounted in a particular manner within the casing and adapted to project light rays forwardly from the upper half of the casing quite similar to the action of an ordinary parabolic reflector but with the lower 65 portion of the reflector so constructed that it serves to project the light upwardly to the upper portion of the reflector for being projected downwardly and outwardly by the latter for concentrating the light on 70 a roadway directly in front of the vehicle. This reflector, indicated at 13 may be described as consisting of a section of a parabola, the lower front portion of which is directed upwardly toward the longer axis of 75 the geometric figure.

It will be seen that the floor or lower portion of the reflector approximates a plane at 15, the same being inclined sharply forwardly and upwardly from the portion 16 of the reflector. The whole of the interior surface of the reflector 13 constitutes a reflecting surface.

The front edge of the reflector 13 is formed and bent downwardly to provide a 85 semi-circular shutter 17 which is disposed behind the lens 11 and closes all that portion of the front of the casing 10 below the points of projection of the light beams.

At 18 is a socket in which a lamp L of 90 any suitable nature may be fitted, and the usual wires 19 lead thereto through an opening at 20 in the casing.

The outer side of the upper portion of the reflector 13 is provided with a circular opening as at 21 that is in substantial alignment with an opening in the outer side of the casing 10 that is closed by means of a colored 95 relatively small lens 22. The lens 22 of the right hand lamp of a motor vehicle will be 100 of a different color from a similar lens of the other lamp of the vehicle, so that when the light shines therethrough from the interior of the reflector, one may determine or distinguish the right and left hand sides 105 of an approaching vehicle, and thereby ascertain in which direction the vehicle is travelling.

The reflector 13 is hinged at its upper forward portion as indicated at 23 to the top 110 of the casing 10, for vertical swinging movement, and associated with the lower rear

portion of said casing 10 is an adjusting screw 24, by means of which the reflector may be tilted for directing the beam at the desired forward and downward angle onto the road.

By means of the above mounting of the reflector, the latter may be set to direct the beam downwardly onto the road at the desired distance ahead of the vehicle, whereby proper illumination is had without directing the beam of light upwardly into the eyes of approaching parties and thereby complying with certain State and town ordinances requiring this to be done. As shown, the adjusting screw 24 is threaded through a nut 25 fixed in an opening in the lower portion of the casing 10 and having its inner upper end swivelled as generally indicated at 26 to the reflector 13 whereby the adjusting screw may be freely rotated relative to the reflector for effectively tilting the latter. In order to securely maintain the adjustment of the reflector 13, a jamb nut 27 is threaded upon the adjusting screw 24 against the under surface of the bottom of the casing 10, and for permitting the tilting movement of the reflector 13, the wires 19 are provided with sufficient slack within the casing 10.

With the parts assembled as shown and described above, the light from the lamp passing upwardly acts upon the upper portion of the reflector 13 the same as in any other parabolic reflector, said light being projected forwardly in parallel lines. Thus, the effect of the reflector with respect to parts thereof above the horizontal plane of the focal axis of the casing is substantially the same as in any other lamp having a parabolic reflector. The effect of the lower portion of the reflector, is to concen-

trate a considerable portion of the light which may be directed upon the roadway in front of the vehicle by properly tiltably adjusting the reflector, at the same time providing a moderate amount of diffused light without the accompanying glare.

From the above description, it is believed that the construction and operation, as well as the advantages of the present invention will be readily understood and appreciated by those skilled in the art.

What we claim as new is:

An automobile headlight comprising a substantially cylindrical casing open at its front end, a removable lens closing said front end, a substantially parabolic reflector disposed diagonally within the casing in a forwardly and upwardly inclined position, a forwardly and outwardly inclined flat bottom closing the lower side of said reflector, the upper end of said bottom terminating in spaced relation from the corresponding end of the parabolically shaped reflector and being bent laterally downward from the latter to provide a substantially semi-circular shutter, the inner surface of said bottom being covered with light reflecting material, a lamp disposed within the reflector at the lower end thereof and spaced above the juncture of the lower end of the bottom with the corresponding end of the main reflector, means pivotally connecting the forward and upper end of said reflector to said casing, and adjusting means for the lower end of the reflector interposed between the latter and the casing.

In testimony whereof we affix our signatures.

CHARLES J. KUNTZ.
EDWARD A. LAURENT.
